UNITED STATES PATENT OFFICE

2,498,102

SUCTION CLEANER

Harry B. White, Canton, Ohio, assignor to The Hoover Company, North Canton, Ohio, a corporation of Ohio

Application June 23, 1945, Serial No. 601,177

14 Claims. (Cl. 183—58)

1

The present invention relates to suction cleaners in general and more particularly to an improved bag-cleaning mechanism in a suction cleaner. More specifically the invention comprises a tank type cleaner in which collected foreign material can be removed from the filter by operator-operated means while in place in the machine.

It is an object of the present invention to provide a new and improved suction cleaner. It is another object of the invention to provide new and improved filter-cleaning means in a suction cleaner. A still further object of the invention is to provide a new and improved tank cleaner in which foreign material can be dislodged from the dirt filter and emptied onto a receiving surface without the necessity of removing the filter from the cleaner. Still another object of the invention is to provide a tank type suction cleaner in which, upon the machine being placed upon one end, the operator can clean the dirt filter by the application of a force to effect the vibration and shaking of the filter. Still another object of the invention is to provide a tank type cleaner adapted to rest, in the filter-cleaning operation, with an open end upon a supporting surface, and in which manually operable bag-shaking means are provided by which the operator can shake the filter to dislodge foreign material which falls upon the supporting surface. A still further object of the invention is to provide a bag-shaking mechanism by which the operator, by the exertion of a linear force, shakes the filter bag to dislodge foreign material therefrom. A further object of the invention is to provide a tank type cleaner having a bag-shaking mechanism including a normally retracted operating pedal which moves into a projecting operating position upon placing the machine in a bag-cleaning relationship. These and other more specific objects will appear upon reading the following specification and claims and upon considering in connection therewith the attached drawings to which they relate.

Referring now to the drawings in which a preferred embodiment of the invention is disclosed, and in which the same reference character refers to the same part throughout:

Figure 1 is a longitudinal vertical section through a cleaner constructed in accordance with the present invention;

Figure 2 is a transverse vertical section upon the line 2—2 of Figure 1 and discloses the coil spring which is loaded in the bag-shaking operation;

2

Figure 3 is a partial bottom view of the cleaner looking in the direction of the arrows upon the line 3—3 of Figure 1, part of the outer casing being broken away and the actuating pedal being shown in its operative position;

Figure 4 is a partial showing of the structure illustrated in Figure 3, the actuating pedal being moved to the inoperative or retracted position;

Figure 5 is a view looking in the direction of the arrows upon the line 5—5 of Figure 3.

A tank type cleaner is illustrated in the drawings and is seen to comprise an outer elongated casing 1. Casing 1 is slidably supported by longitudinally extending runners 2. Its opposite ends are closed by end caps 3 and 4, each of which is respectively provided with a receiving seat 5 and 6 for a dusting tool hose unit. Cap 4, at the suction end of the machine, is removable, being provided at its lower edge with a depending curved lip 7 which seats within a pocket 8 formed at the end of a sliding lever 9 on the underside of casing 1. Lever 9 is slotted and rides on a headed pin 10, being drawn by a spring 11 to hold cover 4 tightly in place. At the top side of the casing is a manually operable latch 12 adapted to overlie the upper end of the cap and to clamp it against the end of the casing.

The end of casing 1 normally closed by the cap 4 is defined by a fixedly secured end plate 13 which is interiorly flanged and which carries one end of a cylindrical filter 14 positioned within casing 1. A rubber sealing ring 15 is positioned in the outer face of plate 13. The opposite end of filter 14 is mounted upon a second ring 16 to the sides of which are secured rigid brackets 17. Spaced parallel equilength arms 18 and 19 are pivotally mounted at their upper ends on each bracket 17, the lower ends of arms 18 being rigidly attached to shaft 21, and the lower ends of arms 19 pivoted on pins 22. The shaft 21 is rotatably mounted and the pins 22 rigidly supported in a bracket 23 attached to the bottom of casing 1. A coil spring 24 encircles the shaft 21, one of its ends being connected to

the shaft and its opposite end extended under a fixed bracket 25. Spring 24 at all times exerts a rotating force upon the shaft 21 which tends to pivot the arms 18 in a counterclockwise direction as viewed in Figure 1, that is, tends to move the ring 16 rearward in the cleaner thereby drawing the bag 14 taut. It is to be noted that the parallelogram mounting of the ring 16 insures that it will remain vertical in all of its longitudinal positions within its range of movement.

Between the filter bag 14 and the end of the cleaner closed by cap 3 is positioned the motor-fan unit comprising a driving motor 26, the casing of which is secured to an adjacent fan chamber 27 having an inlet port 28 and an exhaust port 29. Within the chamber 27 upon the extended rotatable shaft of motor 26 is mounted a pair of rotatable fans 31 which are spaced by a non-rotating guide vane element 32.

The forward end of the motor-fan unit 26, 27 is supported resiliently by a rubber ring 34 in a bulkhead 35 fixedly secured within the casing 1. The rearward end of the unit is supported by a second rubber ring 36 in a bulkhead member 37 also secured in casing 1. Member 37 is perforated, as indicated at 38, and cooperates with a removable perforated cup element 39 to form a final filter chamber 41 within which is positioned any suitable filtering air-permeable material which may, if desired, be impregnated with a volatile odorizing substance.

Electric current to the motor 26 is carried by leads 46 which enter through the casing 1 via the manually operable switch 47 which forms one end of the flexible handle 48.

With the end cap 4 removed and the cleaner tilted upon its end the flat end ring 13, and particularly the seal 15 thereon, is adapted to rest in substantially sealing relationship on a flat supporting surface. The bag 14 is positioned above and is open to the supporting surface. To vibrate and shake the bag with the cleaner so positioned there is provided an operator-operable mechanism which includes a foot pedal 51 pivotally carried at the end of a longitudinally slideable square rod 52 which extends from within the casing 1 into a recess 53 formed in the external underside thereof. Rod 52 passes from the casing through a suitable sealed joint indicated generally at 54. Pedal 51 is normally in the retracted position, illustrated in Figure 4, as a result of its lower end being connected by a pin 55 to the slotted end of a connecting link 56. The opposite end of link 56 is pivoted to the underside of the casing 1 at 57 and the lever 9 pivotally connects thereto at 58 a short distance from the pivot point 57. With the end cap 4 in place the lever 9 is pulled outwardly by the cooperation of lip 7 with the cup 8 at the end of lever 9 and the link 56 is pivoted in a clockwise direction, as viewed in Figures 3 and 4, and the pedal 51 is moved into the inoperative position shown in Figure 4. With the cap 4 removed, however, lever 9 is released and the spring 11 pulls the link 56 in a counterclockwise direction. The link 56, as it pivots from the position of Figure 4 to that of Figure 3, forces the end of the pedal 51 carrying pin 55 inwardly and moves the pedal into its outer operative position as shown in Figure 3.

The inner end of the square rod 52 is formed as a cylindrical extension 61 which is slidably supported by a support 62 secured to the bulkhead 35. A coil spring 63 encircles the extension 61 of the shaft between the bulkhead 35 and a pin 64 at the outer end of the shaft and at all times exerts a force which urges the shaft 52 inwardly so as to hold the lever 51 at the upper or left end of the recess 53, that is, in the position illustrated in Figures 1, 3 and 4. A force upon the pedal 51 effects the movement of the shaft 52 and the compression of the spring 61. To transmit this force to the bag-supporting ring 16 there is provided a sloping sided pivoted pawl 65 carried by a pin 60 on shaft 52. A coil spring 66 is connected to pawl 65 and to the underside of shaft 75 passed through the final filter 41. Should the

52 and at all times exerts a pivoting force which tends to move the pawl 65 in a counterclockwise direction, as viewed in Figure 1, to the extent permitted by the pin 67 to which the spring 66 is attached.

Fixedly mounted upon the arm-carrying rotatable shaft 21 is a lever arm 71 which carries a roller 72 at its outer end which is positioned as to contact the sloping or inclined side of pawl 65. That element moves toward the roller 72 in the movement of the shaft 52 under the actuation of a force applied to the pedal 51 moving it to the right as viewed in Figures 1 and 3. This direction would be downward with the machine tilted on its end. As the pawl moves the roller 72 is forced upwardly along its inclined surface effecting the rotation of the shaft 21 and of the arms 18 carried thereby. Arms 19 connected to the arms 18 by the connecting member 17 and also the ring 16 carrying the end of the bag 14 are moved. The lever arm 71 is so positioned and is of such length that as the roller 72 travels up the inclined edge of the pawl 65 it finally rides over the top thereof at which time the force which has been stored in the spring 24 by rotation of shaft 21 accompanying the pivoting of the arms 18 is released and the arms 18 and 19 move violently in a counterclockwise direction, as viewed in Figure 1, thereby moving the bag ring 16 toward the left to jerk the bag taut. Any collected foreign material is vibrated loose from the bag surface by this shaking action. The shaft 52 together with the pawl 65 can continue toward the right as viewed in Figures 1 and 3 until the pedal 51 reaches the end of the recess 53 at which time, if the operator-exerted force is released, the shaft and pedal move back to their original position, that illustrated in Figures 1 and 3, under the urging of the spring 63. Pawl 65 moves under the roller 72, pivoting downwardly as it does so, and extends the coil spring 66 which immediately snaps it back to its normal and illustrated position upon passing by the roller.

45 The construction is shown and has been described with the machine positioned horizontally but actually the machine would be turned up on end, the cap 4 being removed, and the end plate 13 resting directly upon a supporting floor or surface. This would mean that the operator-exerted force would be exerted downwardly upon the pedal 51 and that the dislodged dirt would fall by gravity onto the supporting surface. The operation can be repeated a plurality of times, as desired, each operation resulting in the violent 50 shaking of the bag as it is drawn taut under the actuation of the operator-provided energy stored in the coil spring 24.

55 The operation of the cleaner constructed in accordance with the present invention may be briefly described as follows: The machine is placed in operation, a suitable dusting tool hose unit being connected to the inlet or suction port 6 in the removable end cap 4. Upon the closing of the manually operable switch 47 electrical current passes through the driving motor 26 and the fans 31 rotate at high speed thereby creating a suction which is effective to draw air in through the hose, into the filter bag 14, through the wall thereof and into the space there-around within the main casing 1, through the inlet 28 of the fan chamber, and to exhaust it through the exhaust port 29 thereof into the space around the motor 26. The air makes its exit from the machine through the exhaust port 5 having first 60 passed through the final filter 41. Should the

operator desire to use the machine as a blower rather than as a suction unit the dusting tools, which may be of any desired and well known type, are attached to the exhaust port 5 in the cap 3 rather than to the inlet port 6 in the removable cap 4.

After the machine has been used for a considerable period of time and foreign material has collected within the filter bag 14 the resistance thereof to the passage of air therethrough increases and, in order to maintain the machine at its maximum cleaning effectiveness, it is desirable to remove the foreign material. To accomplish this the operator releases the manually operable latch 12 thereby permitting the end cap 4 to tilt outwardly at its top, as shown in Figure 1, whereupon the bottom lip 7 thereof can be withdrawn from the pocket 8 in the lever 9. The operator then tilts the machine so that the end plate 13 supports the machine flat upon the surface covering, the machine then having its longitudinal or major axis extended vertically rather than horizontally. The machine is then ready for the bag-cleaning operation proper.

As the operator removed the end cap 4 the effect of the withdrawal of the lip 7 from the pocket 8 was to release the lever 9 whereupon the coil spring 11 on the underside of the cleaner was free to pivot the link 56 in a counterclockwise direction, that is, from the position illustrated in Figure 4 to that illustrated in Figure 3. This effected the movement of the foot pedal 51 from the retracted position of Figure 4 to the extended or operating position of Figure 3. With the machine arranged vertically member 51 extends in a horizontal plane and is positioned near the bottom of the machine. The operator preferably holds the top of the machine, as by the runners 2, and exerts sufficient pressure to maintain a close seal of the open lower end thereof, and specifically the rubber ring 15, with the supporting surface. Simultaneously with one foot he exerts a downward force upon the foot pedal 51. This force results in the movement of the shaft 52 and the pivotal movement of the bag-carrying arms 18 and 19, as described, and the subsequent snapping action on the bag under the actuation of the coil spring 24 as previously described. Preferably the operator will release the pedal 51 permitting it to move upwardly under the actuation of the coil spring 63 on the shaft 52 and will repeat the downward force a plurality of times with the result that all foreign material collected upon the bag surface is dislodged and falls through the open end of the machine to collect upon the supporting surface.

After the operation has been completed the operator need only lift the machine and restore it to its horizontal position thereafter replacing the cap 4 by inserting lip 7 in the pocket 8 and pivoting the cap from the position illustrated in Figure 1 in full lines to the position illustrated by the dotted line upper portion of the cap at which time the operation of the latch 12 will fixedly lock the end cap in place and the machine is again ready for use.

I claim:

1. In a suction cleaner of the type having an enclosing casing housing a filter and suction-creating means to move a dirt-laden air stream therethrough during normal surface cleaning, a removable end cap for said housing adjacent said filter, said casing being adapted to rest upon its open end with said end cap removed, means within said casing to dislodge dirt from said filter

so that said dirt may fall through said open end, and operator-operated means connected with said dirt dislodging means and arranged outside of said casing out of contact with the surface being cleaned during normal surface cleaning, said operator-operated means actuating said dirt dislodging means when said casing is resting on its said open end.

2. In a suction cleaner of the tank type including suction-creating means, a filter, a casing enclosing said suction-creating means and said filter, a removable cover closing an open end of said casing during normal surface cleaning which open end is adapted to make sealing contact with a supporting surface with said cover removed and with said cleaner tilted into its filter-cleaning position, and in which said filter is positioned adjacent said open end, means movably mounting a portion of said filter, means to shake said portion of said filter, and means including an operator-operated member extending outside said casing out of contact with the surface being cleaned during normal surface cleaning, said operator-operated member transmitting an operator supplied actuating force to said filter shaking means to shake said filter to dislodge dirt therefrom so that the dislodged dirt may fall through said open end.

3. In a suction cleaner of the tank type including suction-creating means, a filter, a casing enclosing said suction-creating means and said filter, a removable cover closing an open end of said casing during normal surface cleaning which open end is adapted to make sealing contact with a supporting surface with said cover removed and with said cleaner tilted into its filter-cleaning position, and in which said filter is positioned adjacent said open end; means to dislodge collected foreign material from said filter with the cleaner in its filter-cleaning position so that said dirt can fall through said open end onto an underlying surface, a pedal extended laterally from the lower end of said casing in its filter-cleaning position and out of contact with the surface being cleaned during normal surface cleaning, means mounting said pedal for bodily displacement relative to said casing, spring means urging said pedal to its uppermost position and adapted to bodily return said pedal to said position after being depressed by a downward force thereon, a force-transmitting means to transmit a downward force on said pedal into a dirt-dislodging force at said means to dislodge collected foreign material.

4. In a suction cleaner of the tank type including suction-creating means, a filter, a casing enclosing said suction-creating means and said filter, a removable cover closing an open end of said casing which open end is adapted to make sealing contact with a supporting surface with said cover removed and with said cleaner tilted into its filter-cleaning position, and in which said filter is positioned adjacent said open end; means to vibrate said filter to displace adherent foreign material therefrom so that said material can fall through said open end onto an underlying surface, means to impart an actuating force to said last-mentioned means including manually operated means adapted to receive an operator applied force, and separate means to return said manually operated means to its force-receiving position upon its release from said operator applied force.

5. In a suction cleaner, an elongated casing, means to support said casing movably with its major axis extended horizontally, a removable

cover for the end of said casing, said casing, with said cover removed, presenting an open end adapted to seal upon a supporting surface to support said casing with its major axis extended vertically, a filter bag in said casing with its open end opening toward the open end of said casing, supporting means supporting the closed end of said bag including spring means exerting a force to draw taut the side wall of said bag, and means to move said supporting means to release the tautness in the bag wall and to store energy in said spring and including cam means to suddenly release said supporting means whereupon said spring means jerks said bag wall taut to dislodge collected foreign material.

6. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter bag in said casing with its open end opening toward the open end of said casing, supporting means supporting the closed end of said bag including spring means exerting a force to draw taut the side wall of said bag, actuating means to move said supporting means to relax the tautness of said bag wall and including cam means to abruptly release said supporting means to the action of the stored energy of said spring means, said actuating means including a foot pedal extended laterally from said casing adapted to receive a downward force with said casing supported on its open end.

7. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter in said casing adjacent the open end thereof and through which dirt-laden air through said cleaner passes, means to dislodge dirt from said filter so that it may fall through the open end of said casing onto a supporting surface with said casing supported on said open end, and operator-operated means to actuate said last-mentioned means including a pedal normally extended alongside the exterior of said casing in inoperative position, and means actuated by removal of said cover for moving said pedal into a lateral operative position relative to said casing whereby said pedal may be operated to actuate said dirt dislodging means.

8. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter bag in said casing with its open end opening toward the open end of said casing, a bag frame at the closed end of said bag holding said bag distended, a pair of supporting arms upon each side of said frame mounting said frame for movement toward and from said open end, a spring exerting a pivoting force on said arms to move said frame from said open end and to draw the side wall of said bag taut, and means to pivot said supporting arms against the force of said spring to relax the tautness in said side wall and including means to release said arms to

move under the force of said spring to jerk said bag side wall taut, and operator-operated means to actuate said last-mentioned means.

9. In a suction cleaner, an elongated casing, means to support said casing movably with its major axis extended horizontally, a removable cover for the end of said casing, said casing, with said cover removed, presenting an open end adapted to seal upon a supporting surface to support said casing with its major axis extended vertically, a filter bag in said casing with its open end opening toward the open end of said casing, supporting means supporting the closed end of said filter bag including pivotally mounted means, a coil spring at the pivotal axis of said last-mentioned means exerting a force thereon to draw taut the side wall of said bag, means to move said supporting means to relieve the tautness of said bag and to store energy in said coil spring and including means to suddenly release said supporting means whereupon said spring is enabled to jerk said bag taut to dislodge collected foreign material.

10. In a suction cleaner, suction-creating means, a filter, a casing enclosing said suction-creating means and said filter, filter-shaking means to dislodge collected foreign material from said filter, a removable cover closing an open end of said casing through which said dislodged foreign material may be removed, and means controlled by said cover and connected with said filter shaking means for preventing operation of the latter when said cover closes said open end of said casing.

11. In a suction cleaner, suction-creating means, a filter, a casing enclosing said suction-creating means and said filter, filter-shaking means to dislodge collected foreign material from said filter, a removable cover closing an open end of said casing through which said dislodged foreign material may be removed, and means controlled by said cover for maintaining said filter-shaking means inoperative when said cover closes said open end of said casing, said means connected with said cover and operated upon removal of said cover to release said filter shaking means for dislodging the foreign material from said filter.

12. In a suction cleaner, suction-creating means, a filter, a casing enclosing said suction-creating means and said filter, filter-shaking means to dislodge collected foreign material from said filter, a removable cover closing an open end of said casing through which said dislodged foreign material may be removed, latch means for locking said cover to said casing in closed position, and means connected to said cover and filter-shaking means for urging said cover away from said casing toward its removed position upon release of said latch means.

13. In a suction cleaner, a filter, a casing enclosing said filter, filter-shaking means to dislodge foreign material from said filter, a removable cover closing an open end of said casing through which the dislodged foreign material may be removed, latch means for securing said cover to said casing, and means connecting said cover latch means to said filter-shaking means to prevent operation of the latter when said latch means secure said cover to said casing.

14. In a suction cleaner, an elongated casing, a removable cover for one end of said casing, said casing with said cover removed presenting an open end adapted to seal upon a supporting surface to support said casing in filter cleaning position, filter supporting means including resilient

means to maintain said filter in one position with respect to said casing open end, moving means for moving said filter supporting means against the force of said resilient means to shift said filter to another position, cam means to release said moving means from said filter supporting means and the influence of said resilient means to permit the latter to abruptly snap said filter back to its said one position to dislodge dirt from said filter through said casing open end onto the supporting surface, and operator-operated means for actuating said moving means.
